UNITED STATES PATENT OFFICE.

THURE LARSSON, OF WORCESTER, MASSACHUSETTS, ASSIGNOR TO NORTON COMPANY, OF WORCESTER, MASSACHUSETTS, A CORPORATION OF MASSACHUSETTS.

DRESSING TOOL FOR GRINDING WHEELS.

Application filed September 8, 1918. Serial No. 252,961.

To all whom it may concern:

Be it known that I, THURE LARSSON, a citizen of the United States of America, residing at Worcester, in the county of Worcester and State of Massachusetts, have invented certain new and useful Improvements in Dressing Tools for Grinding Wheels, of which the following is a full, clear, and exact specification.

10 This invention is an improvement in dressing tools used for trimming grinding wheels.

The grinding wheels in most common use are made of abrasive grains, such as aluminum oxide, held together by a ceramic bond, such as vitrified clay material, which has sufficient adhesive strength to prevent rupture of the wheel during rotation and to hold the surface grains in place for a time while grinding proceeds and yet is adapted 15 to break away when the strain becomes excessive and permit new and undulled grains to be presented to the work. The procedure of shaping a wheel, during manufacture and after it has been used and its grinding surface needs renewing, is based on this fact that the bond is weaker than the grain. Hence, to dress a wheel it is merely necessary to rotate the wheel and exert sufficient pressure with a cutting tool against the 20 grinding surface to disrupt the top layer of bond and remove the exposed abrasive grains. For this operation, it is customary to use a dressing tool or dresser mounted on a suitable mechanism for traversing across the 25 wheel face. One type of dressing tool which may be used comprises a freely rotatable cup shaped or hollow conical disk which is forced against the wheel and is rotated thereby. The combination of the pressure 30 and the rolling action of the disk crushes the bond and trims the surface of the wheel.

Since the disk is ordinarily rotated at a high speed and with great pressure against the wheel, often exceeding 1000 pounds, the 35 pivotal mounting of the disk wears away rapidly, this action being accentuated by the dust from the wheel which gets into all the bearings not thoroughly protected. A frequent result of the enormous pressure put 40 upon the disk is to cause the disk shaft to become welded to its thrust bearing. The excessive wear on the various parts soon produces loose bearings, and prevents work of the best character being produced. In fact, 45 this operation must often be carried on with

extreme accuracy and only tools capable of precision work can be used. For example, a loosely mounted disk is liable to cause marks on the wheel and to cut to varying depths. For such reasons the life of a dressing tool 50 heretofore has been short and the operation of dressing wheels has been made expensive because of the necessity for replacing the dressers frequently.

The object of the present invention is accordingly to provide a dressing tool of the character described which will not be subject to the disadvantages above set forth, which is correctly designed to withstand the 55 pressure and strains put upon it, which has bearing members capable of quick and easy adjustment when compensation for the small amount of wear taking place is necessary and which is dust proof for any adjusted position 60 of the bearings.

To the accomplishment of this object and such others as may hereinafter appear, as will be readily understood by those skilled in the art, the invention comprises the general features and combination of parts hereinafter described and more particularly 65 pointed out in the appended claims.

The preferred embodiment of the invention is illustrated in the accompanying drawing, in which:

Fig. 1 is a horizontal section through the dressing tool;

Fig. 2 is a section on the line 2-2 of Fig. 1;

Fig. 3 is an end elevation which is partly 60 in cross section, looking from the right in Fig. 1, the dust cap having been removed; and,

Fig. 4 is a detail view of one of the bearing-adjusting followers.

In the practice of my invention, I have provided a dressing tool comprising a disk 10, herein illustrated as being of a hollow conical form, which is secured to the end of a shaft 11 mounted to rotate in a housing 12, 100 adapted to be adjustably fixed in place on the dressing machine by the usual strap and bolts. The disk is rigidly secured to the shaft by a screw-threaded bolt 13 having a conical head which engages the inside of the 105 disk and clamps it securely against the end of the shaft.

It is apparent that when the disk is forced 110 against the grinding wheel, indicated at 14, with heavy pressure, the resultant end and

side thrusts on the shaft are proportionately severe. In order that the disk may turn freely with the wheel, bearings are provided for the shaft 11 which are made adjustable 5 to take up the wear caused by the severe character of the work so as to avoid the difficulties caused by loose bearings. In the embodiment illustrated, the front end of the tool is provided with an adjustable conical bearing which may be an anti-friction bearing comprising an inner raceway 15, rolls 16, and an outer raceway 17. The outer raceway 17 is loosely engaged in an enlarged bore in the housing 12 and it is positioned 15 longitudinally of the housing by a follower 18 screwed into the bore. The inner raceway 15 surrounds the shaft 11 and abuts against a flange 19 formed integral therewith. It is evident that longitudinal movement of either of the raceways will adjust 20 the bearing. The outer raceway is adjusted by turning the follower 18 within the housing which moves the raceway 17.

In order that the bearing may be conveniently adjusted, I provide suitable adjusting and locking mechanism. While I may utilize a construction such as employed at the other end of the shaft, I preferably provide means for tightening the bearings 25 from outside the housing. One form of mechanism by which this may be accomplished is illustrated in Fig. 2 and comprises a worm 20 loosely engaged in a hole in a boss 21 formed on the housing 12. The worm is in operative relation with the follower 18 through engagement with generally longitudinal teeth 22 cut on its threaded periphery. The worm 20 is held from longitudinal movement within its chamber 30 by two set screws 24, one of which forms a thrust bearing for the worm when it is turned. When it is desired to adjust the bearing, one of the screws 24 is removed and the worm is turned in a clock-wise direction 40 by a screwdriver. Assuming all the screw threads to be right-handed, which is the preferred construction, the upper screw 24 would be removed to take up wear in the bearing, while the lower screw 24 would 45 take the thrust of the worm. The screws 24 serve, when in place as shown in Fig. 2, to lock the worm against accidental rotation and to exclude dust from the interior 50 of the housing.

One feature of the invention relates to the construction by which the bearings are rendered dustproof within the housing. The front or cutter end of the tool is protected from dust by a stuffing box 25 and a dust 55 cap 26. The follower is provided with a central recess to form the stuffing box having the usual packing which is held toward the smaller end of the recess by a spring 27. The stuffing box is closed by a gland 28 threaded on to a reduced portion 29 of the

follower. The gland is provided with holes 30 for a pin or spanner wrench by which it may be firmly seated against the end of the housing 12. The dust cap 26 is mounted on the shaft 11 and rotates therewith. The cap is threaded to receive the end of the shaft and the two parts are secured rigidly together by a locking screw 31. Since the adjacent surfaces of the dust cap 26 and the glands 28 are separated for clearance, I have provided a dust cap construction adapted to reduce the liability of dust entering this interstice. This feature involves making an extended radial and preferably tortuous passage between the rotating cap and the stationary gland. As shown, this construction may involve complementary annular flanges on the two parts, which are so offset as to produce a broken passage through which the dust must travel to reach the bearing. The shape and extent of the passage combined with centrifugal action make an effective barrier to the dust. 75 80 85

The other end of the shaft 11 is supported laterally by bearings adapted to take radial and end thrusts. My preferred construction involves a radial ball bearing 32 and an adjustable thrust bearing. The shaft is reduced at 33 to accommodate the inner raceway 34 of the bearing 32 and again at 35 to accommodate a sleeve 36 of the thrust bearing. The moving raceway 37 of the thrust bearing is carried by the sleeve 36 while the fixed raceway 38 is supported by a self-aligning annular member 39 which is in turn supported against longitudinal movement by a follower 40 threaded into the housing 12. The inner member 34 of the radial bearing and the sleeve 36 of the thrust bearing are rigidly secured to the 95 shaft 11 by a collar 41 and nut 42, as is clearly shown in the drawing.

It will be apparent that rotation of the follower 40 will take up the wear in the thrust bearing or move the shaft longitudinally if desired. As the rear of the housing is readily accessible, the worm actuator for the follower 18 on the front of the tool may be omitted if desired. As illustrated, the follower 40 is adapted to be turned by 100 means of a suitable tool inserted in slots 49. 110 115

The follower 40 may be provided with a locking device to prevent its accidental displacement. While I may utilize the construction described above, the locking is 120 preferably accomplished by a key 43 which prevents relative rotary movement between the follower and the housing. The periphery of the follower is provided with a series of slots 44 (Fig. 4), six slots being a convenient number, spaced at suitable intervals, such as alternately 45 and 60 degrees apart. The interior of the cooperating threaded portion of the housing has four similar slots 45 equally spaced. The slots are preferably 125 130

of a depth equal to the depth of the thread so that the key interlocks the two threads. The slots 44 on the follower are so spaced that a slight rotative movement of the follower brings successive pairs of slots into juxtaposition, thereby permitting 24 locking positions to one turn of the follower.

The end of the housing is covered by a cap 46 screwed on to a reduced portion 47 of the follower 40. The cap forms a tight joint with the housing so that the bearings at this end of the tool are thoroughly protected from dust. The bearings are lubricated by oil inserted through an oil hole 15 closed by a screw 48.

Numerous advantages of a dressing tool having the construction set forth will be apparent to those skilled in the art. The novel construction by which dust is excluded from 20 the various bearings provides a tool which will run much longer without adjustment than those heretofore employed. I have furthermore provided a shaft mounting which is adaptable to withstand the strains 25 normally put upon it and which is readily adjusted to a correct condition. When it becomes necessary to take up wear in the bearings, this may be done, without removing the tool from the dressing machine, by 30 removing one of the screws 24 to permit access to the worm 20 at the work-engaging end of the tool and by unscrewing the dust cap 46 at the other end.

Having thus described my invention, what 35 I claim as new and desire to secure by Letters Patent is:

1. A dressing tool for grinding wheels comprising an open ended housing, a rotatable shaft mounted therein and having one 40 end projecting therefrom, a cutting disk on the projecting end, means to exclude dust from the inside of the housing, adjustable radial bearings within the housing adjacent said projecting end of the shaft, radial bearings 45 for the opposite end of the shaft, adjustable bearings for receiving end thrust only, and means for positively adjusting each set of said adjustable bearings independently of the other set to take up radial 50 and longitudinal wear.

2. A dressing tool for grinding wheels having in combination, a housing provided with a series of slots, a freely rotatable shaft, a work-engaging disk mounted thereon, an antifriction bearing for the shaft comprising a pair of raceways, a follower threaded into the housing and arranged to form an abutment for one of the raceways, said follower being provided with cooperating slots, and a key to lock the follower in adjusted position when inserted in said slots formed in the housing and the follower.

3. A dressing tool for grinding wheels

having in combination, a housing having open ends, a shaft therein, a work-engaging disk mounted on the shaft, a thrust bearing near one end of the housing, a dust cap to close said end of the housing, a conical roller bearing near the disk, a follower threaded into the housing to adjust the bearing, a stuffing box between the disk and the bearing, a gland threaded on to the follower and forming one member of the stuffing box, and a cap fixed on the shaft adjacent the gland, the adjacent surfaces of the gland 75 and the cap being complementally offset to form a tortuous passage from the periphery toward the center.

4. A dressing tool for grinding wheels having in combination, a housing, a shaft 80 having a shoulder, a work-engaging disk mounted on one end of the shaft, a radial bearing abutting the shoulder, a thrust bearing abutting the radial bearing, means for clamping one member of each bearing 85 against the shoulder and a follower engaging the other member of the thrust bearing and having a threaded engagement with the housing.

5. In a dressing tool for grinding wheels, 90 the combination of a housing, a shaft rotatably mounted therein, a cap to enclose one end of the housing, a work engaging disk secured to the shaft at the opposite end of the housing and an annular dust cap threaded 95 on to the end of the shaft and counterbored on one side to receive a part of the disk and having a dust excluding flange on the other side.

6. A dressing tool for grinding wheels 100 comprising a housing, a rotatable shaft mounted within and projecting from one end of the housing, a cutting disk on the outer end of the shaft, radial and end thrust bearings for the shaft, a dust cap surrounding the shaft and means associated therewith for excluding dust from the bearings and means for adjusting a bearing from without the housing to take up wear.

7. A dressing tool for grinding wheels 110 comprising a housing, a shaft mounted within and projecting from the housing, bearings near opposite ends of the shaft, a cutting disk on the outer end of the shaft, means including a dust cap around the shaft 115 in the rear of the disk to exclude dust from the bearings, a removable cap on the opposite end of the housing, means operable after removing the latter cap to adjust the adjacent bearing and means for adjusting the 120 bearing at the opposite closed end of the housing from the outside.

Signed at Worcester, Massachusetts, this 4th day of Sept. 1918.

TURE LARSSON.
